William G. McComas

By R. S. & A. Lacey

UNITED STATES PATENT OFFICE.

WILLIAM GLENN McCOMAS, OF COLERAIN, OHIO.

HAY-STACKER.

SPECIFICATION forming part of Letters Patent No. 296,032, dated April 1, 1884.

Application filed September 12, 1883. (No model.)

To all whom it may concern:

Be it known that I, WILLIAM G. McCOMAS, a citizen of the United States, residing at Colerain, in the county of Belmont and State of Ohio, have invented certain new and useful Improvements in Hay-Stackers; and I do declare the following to be a full, clear, and exact description of the invention, such as will enable others skilled in the art to which it app pertains to make and use the same, reference being had to the accompanying drawings, and to the letters and figures of reference marked thereon, which form a part of this specification.

15 My invention has relation to improvements in devices used in the stacking of hay and straw, commonly termed "hay-stackers;" and it consists in the construction, combination, and arrangement hereinafter described and claimed.

20 In the drawings, Figure 1 is an elevation of my machine, looking thereat in about the line indicated by arrow in Fig. 2. Fig. 2 is a plan view of the machine. Fig. 3 is a front elevation of same; and Figs. 4 and 5 are detail views, illustrating the construction in the region of the standard-pivot, all of which will be described.

25 The main frame of my machine is composed of the runners or skids A A, connected by end bars, A' A'', the upright end frame, B, and the inclined guides C. The runners are provided at their front end with clevises a, to which a team may be attached to move the 30 device from place to place. These clevises also serve to receive the pegs with which the machine is staked to the ground when in operation.

35 The upright frame B is composed of the posts B' B'', secured at their lower ends to the under frame, at the rear of and near the opposite sides of same, as shown, while their upper ends are brought close against the opposite sides of the head-block B'', and are connected by the bolt b, which also serves as a 40 means for the fastening thereto of the guides C C, which are inclined downward, and supported at their opposite ends on the front cross-bar, A'. These guides are separated, as 45 shown, providing a way for the standard hereinafter described. Through these guide-bars,

I form a series of pin-holes, c c, to permit the insertion of the rope and pins c', which support the standard in its upright position. I also form an opening to receive the pin c'', 55 which supports the standard when lowered, as will be described.

The windlass D is journaled in the upright posts, and is provided with peripheral mortises to receive the levers D', by which it is 60 revolved.

The trunnion-bar E is journaled at its opposite ends in the posts B' of the upright end frame, and extends between the same at a point about midway the ends of said posts, as 65 shown.

The standard F is provided near its lower end with a transverse mortise or slot, f, cut in its forward edge. The upper and lower walls, f' f'', of this mortise are rounded, as 70 shown, to permit the rocking of the standard laterally. The smallest height of the mortise is about equal the trunnion-bar, which is placed in the mortise, and the latter is of slightly less depth than the thickness of the bar E, 75 so that when the said bar is placed in the mortise its outer edge projects slightly out, to serve as a bearing for the clamping-plate f'', which is secured to the standard above and below the mortise f by bolts f', and bears 80 tightly against the trunnion when the bolts are drawn up, and clamps the standard and trunnion tightly together at any point to which the standard may be adjusted, as will be described. A plate, f'', is secured in the base of 85 the mortise f, and a clip, f'', extends around the standard and has its opposite ends secured to the said plate. This prevents the twisting of the standard when the latter is loosened from the trunnion in the manner described. By the before-described means the standard is secured to its pivot, and it extends thence up through between the guide-bars C. 90

To the upper end of the standard I secure the bars F' F'', the former secured near its rear end to the standard, and extending forward, while the latter is secured midway its ends to the standard, and extends laterally, with its outer ends connected by bars F'' with the forward end of the bar F'. The bar F'' is extended beyond the end of bar F'', so as to project out from over the runner or base frame of 100

the machine. This bar F^3 serves as a support for the rail F^4 , on which the hay elevator and carrier G is placed.

The hay elevator and carrier illustrated is 5 one already patented to me. I do not regard the description of its construction and operation essential here, inasmuch as any other well-known carrier might be substituted for it.

I secure the suitable catch devices on the 10 track near its rear end, and the carrier is connected to rope G' , which extends along the front end of rail over pulley G^2 , thence to pulley G^3 , secured at the outer end of bar F^3 , and thence under pulley G^4 , secured to rail or skid 15 A , where it is secured to a horse or other means employed for elevating the carrier devices.

The load is discharged by means of a trip-rope attached to the fork and held by the operator, as will be understood.

In order to bring the carrier back to its starting-point, it might be secured to one end of a rope, the opposite end of which would be extended over a guide-pulley at the rear 25 end of the rail, and thence over a pulley secured at one end of the bar F' , and provided with a weight; or other means might be provided to secure its automatic retraction; or it might be drawn back by the operator.

30 The rope D^2 has one end made fast to the windlass D , and its opposite end is carried up over pulley b' , journaled in the head-block B^2 , and is made fast to the standard, so that the turning of the windlass will effect the raising 35 and lowering of the said standard, as will be readily understood.

When the device is to be moved from place to place, the standard is lowered to the position indicated in dotted lines, Fig. 1, resting 40 on the pin c^2 , and the bar F' rests on front bar, A' , and it is dragged to the point where it is desired to build the stack or rick. It is then staked to the ground and the windlass turned to elevate the standard, which is held at proper 45 point by pins c' .

If the machine be located on inclined ground, it may be adjusted back, as indicated in dotted lines, so the standard may be set in a true vertical position with reference to the length 50 of the machine; and in case of its lateral inclination by reason of inequalities or slant of the ground, I loosen the bolts f^4 , slip the standard to either side, as required, and tighten the bolts. This is clearly shown in Fig. 5. 55 The end of bar f' and rail will extend over the stack, while the rear end of the rail will project over the load of hay, which can be readily transferred to the stack.

Guy-ropes H are secured to the forward 60 ends of the beams $F' F^4$, and are adapted to extend laterally over the stack and brace and steady the device in the operation of the same.

Having thus described my invention, what I claim, and desire to secure by Letters Patent, 65 is—

1. In a hay carrier, derrick, or stacker, a

pivoted standard provided on its upper end with a carrier-track and the necessary ropes and pulleys, whereby the carrier is operated, substantially as and for the purposes specified. 70

2. In a hay-stacker, the combination, substantially as set forth, of the supporting-frame, a standard pivotally supported thereon, and a carrier-track formed on the upper or free end of the standard, together with the 75 necessary operating mechanism, substantially as described.

3. In a hay-stacker, the combination of the supporting-frame, a pivoted standard, means whereby this standard may be secured at any 80 suitable angle in vertical plane with its pivot, and the necessary operating mechanism, substantially as set forth.

4. In a hay-stacker, the combination, with the supporting-frame, of the standard pivoted 85 thereto, means whereby this standard may be adjusted to any desired angle radial to its pivot and laterally thereto, and the necessary operating mechanism, substantially as set forth. 90

5. In a hay-stacker, the combination, substantially as set forth, of the base or supporting frame, the upright frame mounted at one end thereof, the inclined guides extended from the upright frame to the opposite end of the 95 base-frame and separated, as described, the standard suitably pivoted and movable in a vertical plane between the inclined guides, the rail secured on the upper end of the standard, and the necessary operating mechanism, 100 substantially as set forth.

6. In a hay-stacker, the combination of the supporting-frame, a vertical standard, a pivot or trunnion bar journaled in the supporting-frame, and means connecting the standard 105 and trunnion-bar, whereby the standard may be adjusted laterally, substantially as set forth.

7. In a hay-stacker, the combination, with the necessary framing, of the standard constructed with transverse mortise having its 110 upper and lower walls rounded, as described, the trunnion-bar secured within this mortise and journaled in the framing, and the clamping-plate placed over the mouth of the mortise and bearing against the trunnion-bar, substantially as set forth. 115

8. In a hay-stacker, the combination, with the supporting-frame, of the standard mounted thereon and provided with the track, a hay elevating and carrying device, and the necessary operating mechanism, substantially as 120 specified.

9. The hay-stacker, substantially as described and shown, composed of the movable base-frame, the windlass journaled in the upright frame, the inclined guides, the pivoted standard adjustable in a vertical plane and laterally, as described, ropes connecting the windlass and the standard, the track mounted on the standard, an elevating and carrying 125 device, and the necessary operating mechanism, substantially as set forth.

10. A portable hay-stacker provided with the standard having a track formed thereon and adapted to receive a hay elevating and carrying device, substantially as specified.

5 11. In a hay-stacker, the combination, substantially as hereinbefore set forth, of the upright frame, the trunnion, the standard, the clamping-plate, the plate f^6 , and clip f^7 , all arranged and operating substantially as set forth.

12. The combination, in a hay-stacker, of

the supporting-frame, a standard, a track supported on and extended in advance of the standard, and the guy-ropes secured to and extended laterally from the forward end of 15 the track, substantially as set forth.

In testimony whereof I affix my signature in presence of two witnesses.
